(57) **CLAIM**

The ornamental design for a sprayer shroud, as shown and described.

DESCRIPTION

FIG. 1 is a perspective view showing the sprayer shroud; FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines appearing in FIGS. 1-7 disclose environment related to the claimed design, and therefore form no part of the claimed design.

1 Claim, 3 Drawing Sheets

FIG. 1**FIG. 2****FIG. 3****FIG. 4****FIG. 5****FIG. 6****FIG. 7**
